UNITED STATES PATENT OFFICE

129,398

DESIGN FOR A COMBINED CARD AND TUBING DISPLAY

Foster G. McGaw, Chicago, Ill.

Application January 30, 1941, Serial No. 98,515

Term of patent 7 years

To all whom it may concern:

Be it known that I, Foster G. McGaw, a citizen of the United States, residing at Chicago, county of Cook, and State of Illinois, have invented a new, original, and ornamental Design for a Combined Card and Tubing Display, of which the following is a specification, reference being had to the accompanying drawing, forming a part thereof, in which:

and tubing display showing my new design; and Figure 2 is an enlarged fragmentary transverse sectional view, taken along the line designated by numeral 2—2 and in the direction indicated by the arrows.

I claim:

The ornamental design for a combined card and tubing display, as shown.

FOSTER G. McGAW.
